UNITED STATES PATENT OFFICE.

LINDLEY L. JOHNSON, OF GREENVILLE, TEXAS.

DESIGN FOR A CHANGE-HOLDING PLATE.

46,128.

Specification for Design.

Patented July 21, 1914.

Application filed May 5, 1914. Serial No. 836,553. Term of patent 7 years.

To all whom it may concern:

Be it known that I, LINDLEY L. JOHNSON, a citizen of the United States, residing at Greenville, in the county of Hunt and State of Texas, have invented a new, original, and ornamental Design for a Change-Holding Plate, of which the following is a specification, reference being had to the accompanying drawing, forming part thereof.

The figure is a plan view of a change holding plate showing my new design.

The design preferably is to be etched upon the under surface of the glass.

I claim—

The ornamental design for a change holding plate, as shown.

LINDLEY L. JOHNSON.
